PLATEN PRINTING PRESS

Artur Büttner, Heidelberg, Germany, assignor to
 Schnellpressenfabrik Aktiengesellschaft Hei-
 delberg, Heidelberg, Germany

Application February 8, 1933, Serial No. 655,842
 In Germany February 16, 1932

2 Claims. (Cl. 271—5)

This invention relates to a platen printing press having means for automatically feeding and delivering the sheets; the invention can be employed in connection with such platen printing presses, in which the feeding and delivering device forms a unit with the press, as well as with such platen printing presses in which said devices constitute a separate aggregate which is merely attached to the press and operatively connected with the same.

With all these presses considerable difficulties are encountered in making the attendant quickly versed with the adjustments and readjustments necessary for proper working of the press. It is well known that the feeding and the delivery pile as well as the tipping movement of the feeding sucker must be regulated with respect to the strength of the sheet to be treated. Thus, for example, the feed of the delivery pile and the tipping of the sucker must be different with heavy papers than with thin papers.

Formerly, considerable difficulties arose when a change of the paper to be treated required the rapid and correct adjustment of the necessary parts. Since the result of the various adjustments could not be stated beforehand, and since even after long acquaintance with the machine in question, the necessary adjustments could not be made with sufficient safety and speed, many try-outs were necessary whenever the paper was to be changed, and this led to a loss of time and material. Particularly, up to this time, no assurance was given that the tipping of the suckers as well as the movement of the pile was in conformity with the strength of paper to be treated. Only when both adjustments met the necessary requirements was frictionless operation and the attainment of great working capacity possible.

The desired advantages are obtained by this invention.

By means of this invention, it is possible even for an unskilled workman, upon a change of paper to ensure safely and instantaneously the necessary adjustment of the pile and the tipping sucker to bring them into conformity. Furthermore, it is possible to overcome any inaccuracies in the adjustment during the operation of the machine without making any previous tryouts.

The invention is illustrated diagrammatically and by way of example on the accompanying drawings, on which Figure 1 is a perspective illustration of a platen printing press designed according to this invention, the press being shown in front-view. Figure 2 is a side-view of the

press seen from the right where there is the sheet delivery device, this figure being drawn to a reduced scale relatively to Fig. 1. Figure 3 is a side-view seen from the left, the scale being larger than that of Fig. 1. Figure 4 shows, chiefly in section, details, and Figure 5 is an end-view of these details, seen in the direction from the right to the left of Fig. 4.

For the adjustment of the sucker tipping-over device, which adjustments must be different according to the kind and the thickness of the sheets to be printed, a graduated scale 9 (Figs. 1 and 3) is provided which co-operates with a pointer 6 formed by the free end of a lever 7 connected with the mechanism for tipping-over the suckers 1. Adjusting the degree of the tipping-over of the rod 2 which has the suckers 1 attached to it is effected by turning the knurled nut 3 which is located in the forked end of a member 4 projecting forth from the frame of the machine. A threaded spindle 5 passes through said forked end of member 4 and through said nut 3, and by turning this latter said spindle 5 will be axially moved whereby also the lever 7 will be turned, in that it is jointed to the upper end of the said spindle 5; the pointer 6 will, thus, be moved along the graduated scale 9. 8 denotes a bolt or pivot on which the lever 7 is located. To the lever 7 is hinged an arm 10, the other end of which is hinged to a lever 11. 30 This lever 11 is provided with a curved groove in which is located a roll 13 attached to a lever 12 which is connected with the rod 2 bearing the suckers 1, as has already been mentioned. If the lever 7 with its pointer 6 has been so turned, i. e. 35 adjusted, as to point for instance to the word "Card-board" on the scale 9, the lower face of the suckers 1 will be located parallel to the surface of the feeding-pile p. If the pointer 6 points to the word "Tissue-paper", the sucker rod 2 will 40 be tipped rearwardly in the usual manner. The suckers 1 deliver in known manner the sheets to be printed to the feed and delivery grippers 15 that rotate in a plane parallel to the platen 14, as more clearly described and shown in Letters 45 Patent 1,601,214 and 1,653,838. The position of the grippers 15 when they receive the sheets from the suckers 1 is, however, not influenced by the above-mentioned adjustments, but remains as it had been. For delivering the sheets to the grippers 15, the sucker rod 2 is moved up and down, as indicated in Fig. 3 in dotted lines (positions I, II, III). When the rod 2 is moved downwardly, it assumes that position which corresponds to the adjustment at the scale 9.

For adjusting the extent of the upward movement of the feed table 16 which carries the paper pile p a graduated scale 17 (Figs. 1 and 3) is provided which states the several paper thicknesses. 5 This scale co-operates with a pointer 19 of a hand-lever 18 which acts upon the mechanism for the re-adjustment of the upward movement for the feed pile p . Said scale 17 is affixed to a lever 20 which is loosely supported upon the bolt or pivot 8 that carries also the lever 7. The lever 18 with a pointer 19 is secured to the bolt 21 by means of a pin, and also an eccentric 22 is affixed to this bolt 21, but this latter itself is turnable in the lever 20. Feeling for the height of the pile 10 p is effected by the rod 23 which is fixed to a lever 24. A bolt 25 turnably connects this lever 24 with a bearing head 26 secured to the upper end of a vertically movable rod 27 guided in the frame of the press. When the eccentric 22, the 15 position of which at the time being is secured by locking rests, is turned by means of the pointer lever 18, 19, an extension of the lever 24 which bears upon said eccentric will vary the position of the feeler rod 23 on the pile p . When the pointer 19 points to the word "Card-board" on the scale 17 the paper will get to the bottom face of the suckers 1, whereas at adjustment on the scale 17 to "Tissue-paper" a distance of about half an inch remains between the upper sheet 20 of the feed pile and the bottom face of the suckers 1, as the thin paper must jump onto the suckers 1, in order to attain a better separation of the sheets.

The bolt 21 of the pointer lever 18, 19 is loosely engaged by a rod 28 which is movably connected at its lower end with a double-armed gear lever 30 by a bolt 29. This lever is forked and in this fork is guided the bolt 31 of a feed pawl 32 which engages a ratchet wheel 34. The pawl 32 is hinged to a bell-crank lever 33 which is loosely turnable on the shaft 35 of said ratchet wheel 34. The pawl-lever 32, 33 is actuated from a shaft of the press, not shown, by means of a rod 36. The ratchet wheel 34 is fixed to the shaft 35 and by gear wheels 35¹ and 35² the rack 37 for the feed pile p is moved upwardly, whereas the rack 38 for the delivery pile p^1 is moved downwardly at the same extent. For the sake of security and safety also a counter-pawl 39 for the wheel 34 is provided. 40 denotes a manually operable crank for quickly re-adjusting the piles p and p^1 , if so required.

When the sucker bar 2 has been moved downwardly, and when the uppermost sheet has been sucked on, the pile height is felt by means of the feeler-rod 23 and the pawl 32 is moved to and fro in disengaged position over the ratchet-wheel 34 by the above-described means, or if again a feed movement is requisite the pawl 32 engages the wheel 34 and moves the feed pile p upwardly for a certain short path and the delivery pile p^1 downwardly also for a certain short path.

In Fig. 3 the numeral I shows the position of the suckers 1 when a sheet is being sucked on; in the position II the sheet is delivered over to the grippers 15, and III indicates the uppermost position of the suckers 1, in which the sheet delivered over to the grippers 15 can freely swing through below said suckers. From the position 60 III the suction rod is again moved back into the position I, whereafter the same procedures are continually repeated.

The upward and downward movement of the entire mechanism is effected by a lever 41 which 70 is oscillated on a pivot 41¹ by means of a cam

(not shown). This lever 41 is connected by means of a bolt 41² to a casing 42 (Figs. 1 and 3) attached to the vertically movable rod 27 by means of a bolt 43.

In the casing 42 (Figs. 4 and 5) is housed the mechanism for reversing the press to no-load running. In a bore 44 of this casing 42 is shiftable a piston 44¹ which is subjected to the pressure of a compressive spring 45 that continually tends to press the piston outwardly and is normally held in the position shown in Fig. 4. Into the bore 44 enclosing said spring terminates the suction pipe 46, the other end of which communicates with the suction pump 47 (Fig. 2), and the branch 48 (Fig. 5) communicates with the sucker rod 2 by means of the pipe 46¹ (Fig. 1). As long as a sheet is being sucked on by the suckers 1, the pressure below atmospheric pressure in the bore 44 is such a one that the piston 44¹ is pressed inwardly by the pressure of the atmospheric air, whereby a disengaging lever 49 that is turnable at the casing 42 on a pivot 50 and is engaged by a pin 44³ of the piston rod 44² will be turned in the direction of the casing 42. If, however, no sheet is being sucked on or if the suckers 25 1 lose the sheet they have sucked on, the piston 44¹ is not moved inwardly and the disengaging lever 49 pushes when the casing 42 is being moved upwardly against a lever 51 (Fig. 3) fixed to a turnable pivot 52. Also a lever 53 is fixed to said pivot 52 and contacts with the manually operable coupling lever 54 thereby holding the latter in working position. When the disengaging lever 49 on its upward movement pushes on the lever 51, this latter is turned upwardly whereby the 35 lever 53 is turned out of engagement with the coupling lever 54 which stands under the action of springs, not shown, and slides now away laterally. Hereby the driving coupling of the press is disengaged, whereupon the machine comes to a 40 stand-still.

For regulating the pressure exerted by the spring 45 (Fig. 4) a screw 55 is provided, as the height of the pressure below atmospheric pressure must be varied in accordance with the working speed of the machine and with the size of the sheets to be printed.

In order to enable the attendant to effect the various adjustments and readjustments quickly, reliably and effectively, a shield 56 bearing the 50 requisite informations is provided below the adjusting screw 55.

For doing away with the vacuum in that point of time when a sheet is delivered over by the suckers 1 to the grippers 15, a passage 57 branching off from the bore 44 is provided and can be closed by a flap 57¹; this flap is intermittently opened by a rotating cam 58¹ (Fig. 5) acting upon a roller 58 which is provided on the flap 57¹.

In order to prevent the machine from coming to a standstill when a sheet is lacking, viz. in the case of running-in the inking mechanism, the following arrangement and combination of parts has been designed:

Above the piston 44¹ a slide 59 having a circumferential groove 60 is arranged in the casing 42. 65 A grip 61 is affixed to one end of that slide. If this latter is drawn to the right (Fig. 4) by means of said grip 61, the groove 60 will communicate with the suction pipe, as well as with an aperture 70 62 establishing a communication with the outer air, so that the suction ceases and no sheets are fed. At the other end of the slide 59 is a hook-like projection 59¹; when this has been moved to the right (Fig. 4) the disengaging lever 49 will 75

no more push upon the lever 51 when the casing 42 is being moved upwardly and the drive coupling of the press remains engaged. The piston 44¹ remains then in its position. There is, by 5 the provision of the said circumferential groove 60, prevented that the press can again be run with fed paper and working printing members without the automatic disengaging members being active whereby printing on the tympan of the 10 platen is prevented if a disturbance should have arisen in the paper supply.

In order to enable the attendant to operate in proper manner the device for throwing into, and out of, gear the automatic disengaging device, 15 there is provided on the grip 61 a shield bearing inscriptions to that effect.

For the adjustment of the cock 64 (Fig. 1), by 20 means of which the supply of the suction air and the blowing air is regulated, is provided a shield 65 which also bears the proper inscriptions.

For the regulation of the stroke of the pump 25 47 (Fig. 2) is provided a shield 67 which bears also the necessary informations. Another shield 66 gives informations for the adjustment of a vacuum regulating valve 68.

For the adjustment of the blowing air serving in known manner for depositing the printed sheets 30 on the delivery pile p^1 there are shields 71 and 72 provided on the air-cock 69 and on the blowing nozzles 70 and bearing inscription for the proper manipulation.

Further statements as to the manipulations to 35 be made when regulating the sheet feeding and delivering device are provided at the places 73, 74, 75, 76 and 77.

It is a matter of course that the shields, scales 40 and levers provided according to this invention at the places concerned can be arranged also in other manners; it is, however, at all events essential that the members to be employed in feeding and delivering the sheets can be so adjusted with the aid of the inscriptions or statements of

the shields, scales and levers or their equivalents that the effect, or effects, sought to be attained is, or are, attained with undoubtable certainty.

I claim:

1. In a platen printing press, in combination with means for the automatic feeding and delivery of the sheets, suckers adapted for feeding the sheets, a gearing for lifting the feed pile, a feeler adapted to touch the upper sheet of the feed pile and to act upon said gearing for lifting the feed pile; means for moving said suckers and said feeler simultaneously up and down, means for tipping said suckers when feeding the sheet, a manually operable stationary lever for adjusting said moving tipping means, and a scale having indicia so arranged relatively to said lever as to facilitate adjustment; a second manually operable stationary lever for adjusting the position of said moving feeler and a scale having indicia so arranged relatively to said second lever as to facilitate adjustment. 10 15 20

2. In a platen printing press, in combination with means for the automatic feeding and delivery of the sheets, suckers adapted for feeding the sheets, a gearing for lifting the feed pile, a feeler adapted to touch the upper sheet of the feed pile and to act upon said gearing for lifting the feed pile; a vertically guided rod for moving said suckers and said feeler simultaneously up and down, a cam lever hinged to said vertically guided rod and adapted for tipping said suckers, a stationary graduated scale, an adjusting lever having a pointer at one end adapted to cooperate with said scale, a link connecting said adjusting lever to said cam lever, and stationary means for turning said adjusting lever; a second stationary graduated scale, a second adjusting lever having a pointer at one end adapted to cooperate with said second scale, and a cam turnable by means of said second adjusting lever and adapted to vary the position of said feeler, and means for moving up and down said vertically guided rod. 25 30 35 40

ARTUR BÜTTNER.
